UNITED STATES PATENT OFFICE.

THOMAS LA MAIDA, OF NEW YORK, N. Y.

CHART FOR CUTTING GARMENTS.

1,068,143.

Specification of Letters Patent. Patented July 22, 1913.

Application filed October 31, 1912. Serial No. 728,869.

To all whom it may concern:

Be it known that I, THOMAS LA MAIDA, a subject of the Province of Salerno, Italy, residing at New York city, in the county of 5 New York and State of New York, have invented new and useful Improvements in Charts for Cutting Garments, of which the following is a specification.

This invention relates to a chart designed 10 to serve as a guide in cutting skirt patterns, and has for its object to render the art of cutting skirt patterns so plain and simple that any person unacquainted with pattern cutting may, by conforming to the directions, 15 prepare patterns for skirts of any style and size.

With this object in view the device consists of a sheet of suitable material on which are outlined several separate diagrams for 20 as many different kinds of skirts such as the narrow style, the wide or full style, the circular style, etc. On each diagram are lines of perforations and scales of measurements following said lines, by means of which perforations and scales certain fundamental 25 guide marks may be made on the material from which the pattern is to be cut, and by means of which guide marks the remaining outlines of the pattern may be laid out.

30 In the accompanying drawing, Figure 1 is a view of the chart complete; Fig. 2 is a diagrammatic view illustrating the use of the chart; Fig. 3 is a view of a sheet of paper or other material with a complete pattern drawn thereon; Fig. 4 is a view of the pattern cut out.

In the drawings, A indicates a chart which may be of card board or other material, on one side of which are printed or otherwise 40 applied the diagrams which serve as guides for laying off the patterns, three of these diagrams being shown and are lettered B, C and D for narrow, wide and circular skirts respectively. Each diagram comprises a 45 straight line *a* marked "Front" as this line coincides with the front of the skirt, and from each end thereof extends indefinitely two substantially parallel curved lines *b* and *c* about six inches apart, the former being 50 the waist line and the latter the hip line. To prevent confusion between these lines, they are marked in an appropriate manner as by the letter W for the waist line and the letter H for the hip line. On the line *b* is 55 a scale *d* reading from the straight line *a* and divided into inches and quarter inches.

A perforation *e* is made through the chart A on the line at each inch graduation, and continued to the line *a* for a purpose to be described hereinafter. A similar scale *f* divides the line *c* and perforations *g* similarly disposed as the perforations *e* are made through the chart. Perforations *h* spaced apart also follow the line *a* from end to end. 60

To use the chart the following measurements of the person to be fitted are first taken. From the waist line down as far as desired in front, at the side and at the back to get the necessary length; then measure around the waist and hips as usual. The 70 width around the bottom will depend on the particular style of skirt desired, whether narrow, full or medium, plain or plaited. With these measurements known, let it be assumed that a pattern for a narrow skirt is 75 desired. The chart A is placed on a sufficiently large sheet of suitable material E which may be paper, with the line *a* of the diagram B or Form No. 1, near one long edge as shown in Fig. 2. Then with chalk, 80 crayon, pencil or other material mark through perforations *h*, *e*, *g* on to the sheet E the full length of line *a* and from said line along waist and hip lines *b*, *c* for a distance measured by the scale equal to one- 85 half the waist and hip measurements in the manner indicated on Fig. 3. For instance, if the waist measures 26 and the hip measures 40 inches, stop at the perforations numbered 13 and 20 on the respective lines. Then remove the chart and with the chalk or other marking material draw lines *i*, *k* and *l* through the three rows of dots made on the sheet E, as in said Fig. 3. With a straight edge continue the line *i* indefinitely as at *i'* 95 and mark off thereon the length of the skirt in front as given by the measure previously taken, if the length be 38 inches make a mark *m* 38 inches from the waist line *k*. Next, draw from the point *m* a line *n* at a 100 right angle to the line *i'* and extending backwardly indefinitely under the waist and hip lines, on which line *n* make a mark *o* distant from the line *i'* equal to one-half the circumference of the skirt around the bottom. If this measurement be 60 inches the mark *o* will be 30 inches from the line *i'*. Now from the point *o* draw a straight line *p* 105 through the extreme end of the hip line *l* and continue it as far as the waist line *k*. The pattern being thus outlined, it only remains to be cut out and present the appearance 110

shown in Fig. 4. In this style of skirt the line *p* may not touch the waist line *h* as in Fig. 3. This fullness, however, may be taken up by making darts in the goods at the waist line. A pattern cut by this particular diagram can be used only for a narrow, plaited or plain skirt, the width of said pattern at the bottom being not less than three-fourths of the hip measure. For example, if the hip measure be 40 inches, the width of the pattern at the bottom should be about 30 inches, a few inches more or less, will not make any difference.

Diagram C or Form No. 2 can only be used for a wide skirt of any style desired. In this case, the width of the pattern at the bottom should be about one-fourth greater than the hip measure, so that a pattern for a person measuring 40 inches around the hips would require a pattern about 40 or 50 inches wide at the bottom. Diagram D of Form No. 3 is to be used if a wider skirt than that of diagram C is to be desired, such as a circular skirt without darts at the waist line and having full width at the bottom. To cut a pattern by this diagram proceed as heretofore described, the marking through the perforations of the front line and the waist and hip lines from a distance thereon equal to one-half the measurements of the waist and hip. Then remove the chart, mark waist, hip and front lines as before and draw the line *z'*. Then mark on the pattern sheet the front and side lengths and draw a line shaped to these measurements for the bottom of the pattern. If a plait be desired in the same allow for same. Before laying out the pattern observe closely the figure of the person for whom the pattern is designed, and bear in mind the fact that every person is built differently. For this reason additional lines *r*, *s*, and *t* with suitable perforations have been placed on the front of each diagram above the waist line to make allowance for the difference in figures. These lines are spaced about a half inch apart at the front line *a* curving to the rear, and gradually merge into the waist line. For a person with a large or protruding abdomen, one of the lines *r*, *s*, *t*, is to be

followed in marking out the pattern, lowering the same amount at the back but make no change at the side.

What I claim is,—

1. A pattern chart for cutting skirt patterns comprising a sheet of suitable material having on one side a diagram formed of two curved substantially parallel lines spaced apart and connected each at one end by a straight line, each of said curved lines having thereon a single scale of like measurements, beginning at said straight line and continuing throughout its length, said sheet having spaced perforations following said curved lines and the straight line through which marks may be made for the foundation lines of a pattern, and a number of other curved lines and perforations on said sheet running from an extension of said straight line and equally spaced thereon to different points on the waist line, whereby on one of said first-named curved lines the waist measure and on the other the hip measure of the person for whom the pattern is being cut will be laid off.

2. A pattern chart comprising a sheet of suitable material having applied on one side a plurality of diagrammatic figures, each figure comprising a straight line and a curved line extending laterally from each end of a straight line, the two curved lines of each diagrammatic figure differing in direction and curvature from corresponding lines of the other figures, said curved lines connected to each straight line being substantially parallel and each having a single scale of like measurements extending from the straight line, said sheet having spaced perforations following the straight lines and the curved lines whereby guide marks for laying off patterns can be made through said perforations, and a number of curved lines and perforations thereon running from an extension of each of said straight lines and equally spaced thereon to different points on each waist line.

THOMAS LA MAIDA.
